UNITED STATES PATENT OFFICE.

ABRAHAM M. SMOLENS, OF BROOKLYN, NEW YORK.

FIGURE WHEELED TOY.

Application filed September 22, 1926. Serial No. 136,901.

This invention relates to figure wheeled toys and has for its main object the provision of a toy of this nature, substantial and inexpensive in construction and one that will give amusement to children.

Another object of this invention is to provide a toy of this nature with a figure adapted to be rotated by a ground engaging friction wheel.

10. A further object of the invention is to provide the figure in a toy of this nature with a skirt comprising depending and loosely mounted members adapted to be spread out into a horizontal position when the figure is 15 rotated.

A still further object of the invention is to provide the figure in a toy of this nature with loosely mounted depending arms that will spread out simultaneously with the depending skirt members when the toy is drawn along the ground and the figure is rotated.

Other objects and novel features of construction of the toy of my invention will 25 become more apparent as the specification proceeds.

Referring to the drawings forming a part of this specification,

Figure 1 is a side view in elevation partly 30 in section of a toy embodying my invention.

Figure 2 is a sectional view on line 2—2, Figure 1 with some of the parts omitted and

Figure 3 is a fragmental view in elevation showing a modified form of the skirt construction.

Referring to the drawings in detail, in which like numerals refer to the same parts throughout the several views, 5 indicates a base or truck body provided with front and 40 rear ground engaging wheels 6 mounted on shafts 7 loosely journalled in the body 5. A bracket 8 is secured to the underside of the truck 5 and is provided with a vertical slot 9. This slot 9 acts as a bearing for a sleeve 10 upon which is mounted a ground engaging friction wheel 11 upon which rests the base 12 of a figure 13 rotatably and slidingly mounted on a stud or shaft 14 secured at one end to the truck 5 and provided with a head 15 at its opposite end. A hollow rod or tube 16 is secured at one end in the figure base 12 and has mounted at its opposite end a body portion 17 provided with an opening 18. Arms 19 are freely suspended on a flexible

55 cord 20 passing through and suitably maintained in the upper portion of the body 17.

The lower section of the body 17 is provided with an annular groove 21 in which is suitably supported a belt 22 comprising a wire frame 23 upon which are strung beads or other ornaments 24. Loosely suspended from the belt 22 are a plurality of depending members 25 forming a skirt 26.

In Figure 3 I have shown a modified form of the skirt supporting means which comprises pins or projections 27 secured to the body 13 at the belt line thereof and provided with slots 28 in which are loosely mounted depending members 30 of similar nature as the members 25 shown in Figures 1 and 2.

The operation of the toy is as follows: The toy is drawn along the ground by a string or cord 31, and the wheel 11 is rotated in the direction indicated by the arrow (Fig. 1) which in turn causes the figure 13 to whirl or revolve around the stud or shaft 14, which rotation causes the depending members 25 or 30 as well as the arms 19 to spread out and thus simulate a whirling and dancing figure.

It will be readily seen by referring to Fig. 1 that should any of the wheels encounter any unevenness on the ground over which it is propelled, such unevenness will be compensated by the slot 9 in the bracket 8 and the figure base 12 will always be in contact with the wheel 11 and thus will always be free to revolve.

From the foregoing it will be seen that I have provided a toy substantial and inexpensive in construction, one that will give pleasure and amusement to children and one that will operate satisfactorily under all conditions.

Having described my invention, what I claim as new is:

1. In a toy adapted to be propelled along the ground, a base, ground engaging means on the base, a ground engaging wheel rotatably mounted on the base, a shaft secured to the base, a figure resting on the wheel, and loosely mounted on the shaft, and a skirt comprising depending members loosely suspended from the figure adapted to be spread out when the toy is propelled along the ground and the figure is made to rotate.

2. In a toy adapted to be propelled along the ground, a base, front and rear ground engaging wheels rotatably mounted on the base, an additional ground engaging wheel rotatably mounted on the base, a shaft secured to the base, a figure resting on the

wheel and loosely mounted on the shaft, and a skirt comprising depending members loosely suspended from the figure adapted to be spread out when the toy is propelled 5 along the ground and the figure is made to rotate.

3. In a toy adapted to be propelled along the ground, a base, ground engaging means on the base, a ground engaging wheel vertically 10 slideable and rotatably mounted on the base, a shaft secured to the base, a figure resting on the wheel and loosely mounted on the shaft, and a skirt comprising depending members loosely suspended from the figure 15 adapted to be spread out when the toy is propelled along the ground and the figure is made to rotate.

4. A toy adapted to be propelled along the ground, comprising a base, ground engaging 20 means on the base, a ground engaging wheel vertically slideable and rotatably mounted on the base, a shaft secured to the base, a figure resting on the wheel slideably and rotatably mounted on the shaft, a body portion on the 25 figure provided with an annular groove, a

belt supported on the said groove and a skirt comprising depending members swingingly supported on the belt, the said members being adapted to spread out when the toy is propelled along the ground and the figure is 30 made to rotate.

5. A toy adapted to be propelled along the ground, comprising a base, ground engaging means on the base, a ground engaging wheel vertically 35 slideable and rotatably mounted on the base, a shaft secured to the base, a figure resting on the wheel slideably and rotatably mounted on the shaft, a body portion on the figure provided with an annular groove, arms freely suspended from the body, a belt supported in the said groove and a skirt comprising depending members swingingly supported on the belt, the said arms and depending members being adapted to be spread out simultaneously when the toy is propelled 40 and the figure rotates.

In testimony whereof I hereunto affix my signature.

ABRAHAM M. SMOLENS.
